Primary Examiner — Darlington Ly*Assistant Examiner* — Nasim Abdulaziz Ali(74) *Attorney, Agent, or Firm* — Spencer Fane LLP(57) **CLAIM**

The ornamental design for a motor coach, as shown and described.

DESCRIPTION

FIG. 1 is a front and right side perspective view of the motor coach embodying my new design;

FIG. 2 is a front elevation view thereof;

FIG. 3 is a rear elevation view thereof;

FIG. 4 is a right side view thereof;

FIG. 5 is a left side view elevation view thereof;

FIG. 6 is a rear and right side perspective view thereof;

FIG. 7 is a front and left side perspective view thereof; and

FIG. 8 is a rear and left side perspective view thereof.

The broken lines in the drawings depict portions of the wheels of the motor coach that form no part of the claimed design.
